PUZZLE TOY

James J. Nolan, Danbury, and Charles J. Hoyenski, Bethel, Conn.

Application October 6, 1949, Serial No. 119,848

4 Claims. (Cl. 273—156)

1

This invention relates to toy devices so constructed as to be normally strung along an elastic strand, wherein proper assemblage of the toy elements on the strand will produce a resulting mechanical toy, in which all of the elements are firmly held in assembled relationship to each other. More particularly, the invention deals with a puzzle toy of the character described wherein the several elements are so grooved and otherwise formed as to conceal substantially all of the holding strand when the elements are properly and completely assembled.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a perspective view of a toy made according to our invention in assembled position.

Fig. 2 is a vertical sectional view through the toy on the line 2—2 of Fig. 1; and

Fig. 3 is a diagrammatic view of the toy in its extended and unsolved position.

In devices of the type and kind under consideration, it is known to provide a plurality of elements or parts which, when assembled, will construct a toy or article of manufacture and, in most cases, these devices are in the form of building or erector sets but, as such, the various parts are independent and means are required to hold the parts in their assembled relationship.

The purpose of our invention is to provide a complete unitary assemblage arranged upon an elongated strand preferably of extensible material in order to provide a tensional holding of the parts in assembled relationship; thus to construct a resulting toy, it is necessary to solve the problem of proper assemblage of the parts in order to produce the resulting toy. In this way, a child can be kept occupied for a considerable length of time in order to solve the problem of assemblage and, after the toy has been assembled, the child has an operable mechanical toy, particularly, if the resulting toy is of a type including wheels. In this connection, it will be understood that any type and kind of toy or article can be produced in the same manner and, to illustrate one adaptation and use of the invention, the representation of a locomotive is shown.

Considering Fig. 1 of the drawing, here is indicated a perspective view of a toy locomotive which comprises front and rear lower parts 10 and 11 and an intermediate lower part 12. In

assemblage of the toy, the locomotive comprises three other parts disposed above the parts 10, 12 and 11, respectively, namely the parts 13, 14, and 15. Arranged upon the upper portion of the part 15 is a top hood part 16. The parts 10-16, inclusive, may be regarded as body parts. Arranged in suitable sockets 17, 18 and 19 on the upper surface of the part 13 and the part 14 are other locomotive parts such, for example, as the representation of a chimney 20, the representation of a steam exhaust 21 and representation of a bell 22. The part 13 has, on its front surface, two other sockets 23 and 24. The socket 23 is adapted to receive the representation of a headlight 25; whereas the socket 24 is adapted to receive a locomotive cylinder front 26, which will also be referred to as a plug end on the resulting device.

The parts 10 and 12 have, at their lower surface, transverse sockets or recesses 27 and 28, respectively, for reception of axle portions 29 and 30 on wheel parts 31 and 32. These wheel parts have wheels rotatably mounted at the ends of the axle portions 29 and 30, as clearly seen in the drawing. The various parts mentioned may also be characterized as elements of the puzzle in the resulting toy device.

Now considering Fig. 3 of the drawing, it will appear that these parts or elements are united on an elongated strand 33, preferably of strong elastic or elastic and fibrous material in the following arrangement.

One end of the strand has a knot 34 anchored and embedded in the part or element 26. The strand first passes through the axle of the elements 31, 32; then through an elongated aperture 35 in the element 16; then through apertures in the elements 22, 21, 20 and 25, respectively, then through an aperture 36 in the element 13, through an aperture 37 in the element 14 and an aperture 38 in the element 15, an aperture 39 in the element 11 and then through an aperture 40 in the element 12. The last named aperture 40 has an enlarged portion 41 at one end to receive a loop or eye 42 on the element 10 and the other end of the strand 33 is fixed to the eye 42.

In addition to the provision of the various apertures 35-40 for reception of the strand 33, the various parts have grooves in peripheral surfaces to embed the strand in the parts or elements so as to be invisible externally of the toy. This construction provides around the periphery of all of the parts a central slot which is generally identified by the reference character 43 in

Fig. 1 of the drawing and it will be seen from Fig. 2 of the drawing that this slot opens through the front and bottom surfaces of the part or element 10, the lower surface of the element 12, the lower and rear surface of the element 11, the rear surface of the element 15, part of the lower surface of the element 16 and the upper surface of the element 14 and the upper and front surface of the element 13.

In assembling the toy, the element 15 is swung upon the top of the element 11, the element 14 is swung onto the element 12 and the element 13 on top of element 10, after which the elements 25, 20, 21, and 22 are successively placed in position in their respective sockets in the manner clearly seen in Fig. 2 after which the element 16 is arranged upon the element 15, then the two wheel elements 32, 34 are successively mounted upon the lower surface of the elements 12 and 10, respectively, and finally the plug element 26 is placed in the socket 24, which completes the assemblage of the vehicle.

When the various parts or elements are assembled in the manner illustrated in Figs. 1 and 2, a sturdy wheeled toy is provided which can be pushed about or drawn about on a floor or surface, all of the parts and elements being firmly held in abutting relationship to each other.

While it is possible to forcibly separate some of the parts to a slight degree, disassembly of the parts is impossible by virtue of the lock or key construction provided by arrangement of the strand 33 in the slots of the respective parts. However, when quick disassembly is desired, all that is necessary is to forcibly remove the plug part or element 26 and to hold this element in the hand; whereupon the remaining elements will become disassembled by simply shaking the toy and the same will extend themselves along the strand 33 in the relationship indicated in Fig. 3, but with all of the parts disposed in common alinement. In the accompanying drawing, the showing is schematic simply to include the structure clearly on the drawing. It will also be understood that the parts will be in a close assemblage with respect to each other on the strand. In this connection, it is desirable that a relatively free unbinding mounting of the several parts or elements on the strand be provided, so as to facilitate free movement of the parts along the strand in assemblage.

It will also be apparent that in assembling, the strand is tensioned as the various parts are placed in abutting engagement with each other. This insures the firm assemblage of the parts in the resulting toy and, as thus assembled, produces a strong and durable toy.

It will be readily apparent that vehicles of different types and kinds can be produced in the manner defined and sets of such vehicles, for example, a complete train with several cars can be produced, each complete unit being assembled in the manner defined.

It will also be understood that by the type of grooving employed, greater complications can be provided in the solution to the toy assemblage to have toys of the kind under consideration of interest to children of many ages, in fact, of interest to grown folks.

The parts or elements can be composed of any desired material, such as wood, metal or plastic and, in some constructions, the parts can be characterized, for example, as illustrated in Fig. 1 of the drawing to enhance the appearance of the resulting toy.

It is also to be understood that the strand 31 may be said to comprise a binder or key member for holding the various parts in not only the assembled relationship, but also in alined relationship with each other. Where a still more sturdy construction is required, the various parts or elements may be further keyed together as will be apparent.

Having fully described our invention, what we claim as new and desire to secure by Letters Patent is:

1. A puzzle article of manufacture of the class described, comprising a plurality of complementary parts disposed upon an elongated strand, two of said parts being fixed to terminal ends of the strand, the other parts being fixed against displacement from and movable longitudinally of the strand between said end parts and adapted to be positioned on each other to form, in the solution of the puzzle, a unitary assemblage of predetermined character, a number of the parts forming the body of the assemblage, the outer of said body forming parts in the assembly having alined peripheral recesses when assembled for reception of said strand when wrapped around said assemblage to hold it together, and one end part being in the form of a plug insertable into a socket of one of the body parts in holding the various parts in assembled relationship.

2. A puzzle article of manufacture of the class described, comprising a plurality of complementary parts disposed upon an elongated strand, two of said parts being fixed to terminal ends of the strand, the other parts being fixed against displacement from and movable longitudinally of the strand between said end parts and adapted to be positioned on each other to form, in the solution of the puzzle, a unitary assemblage of predetermined character, a number of the parts forming the body of the assemblage, the outer of said body forming parts in the assembly having alined peripheral recesses when assembled for reception of said strand when wrapped around said assemblage to hold it together, one end part being in the form of a plug insertable into a socket of one of the body parts in holding the various parts in assembled relationship, and predetermined body parts having recesses opening through outer surfaces thereof for reception of other parts of the toy arranged on said strand.

3. A puzzle article of manufacture of the class described, comprising a plurality of complementary parts disposed upon an elongated strand, two of said parts being fixed to terminal ends of the strand, the other parts being fixed against displacement from and movable longitudinally of the strand between said end parts and adapted to be positioned on each other to form, in the solution of the puzzle, a unitary assemblage of predetermined character, a number of the parts forming the body of the assemblage, the outer of said body forming parts in the assembly having alined peripheral recesses when assembled for reception of said strand when wrapped around said assemblage to hold it together, one end part being in the form of a plug insertable into a socket of one of the body parts in holding the various parts in assembled relationship, predetermined body parts having recesses opening through outer surfaces thereof for reception of other parts of the toy arranged on said strand, and two of said last named parts including wheels.

4. A puzzle article of manufacture of the class described, comprising a plurality of complementary parts disposed upon an elongated strand,

two of said parts being fixed to terminal ends of the strand, the other parts being fixed against displacement from and movable longitudinally of the strand between said end parts and adapted to be positioned on each other to form, in the solution of the puzzle, a unitary assemblage of predetermined character, a number of the parts forming the body of the assemblage, the outer of said body forming parts in the assembly having alined peripheral recesses when assembled for reception of said strand when wrapped around said assemblage to hold it together, one end part being in the form of a plug insertable into a socket of one of the body parts in holding the various parts in assembled relationship, and said strand being concealed within the alined recesses

of the body parts in the assemblage of said parts.
